INVENTOR
WENZEL F. WEISS
BY Charles S. Evans
HIS ATTORNEY.

UNITED STATES PATENT OFFICE

WENZEL F. WEISS, OF SAN JOSE, CALIFORNIA, ASSIGNOR TO SPRAGUE-SELLS CORPORATION, OF HOOPESTON, ILLINOIS, A CORPORATION OF DELAWARE

EXHAUST BOX

Application filed October 12, 1925. Serial No. 61,943.

My invention relates to devices used in the packing industry for heating the cans or containers after filling, and before capping, so as to exhaust the imprisoned air from the contents of the container.

One of the objects of the invention is to provide an exhaust box characterized by the relatively large number of containers accommodated in relation to the floor space occupied by the exhaust box.

Another object of the invention is the provision of an exhaust box embodying a disk conveyor and in which the structural elements are of improved design and arrangement to increase the general efficiency of the machine, to facilitate manufacturing, and to lessen the cost of production.

Another object of the invention is the provision of an exhaust box embodying a disk conveyor with improved mounting means for the individual disks so that water and steam are excluded from the bearings.

Another object of the invention is the provision of improved means for lubricating the bearings.

My invention possesses other objects and features of advantage, some of which with the foregoing will be set forth in the following description of the preferred form of my invention which is illustrated in the drawings accompanying and forming part of the specification. It is to be understood that I do not limit myself to the showing made by the said drawings and description as I may adopt variations of the preferred form within the scope of the invention as set forth in the claims.

Referring to the drawings:

Figure 1 is a plan view of my exhaust box, the cover being removed and portions of the structure broken away to shorten the length of the view.

Figure 2 is a transverse vertical section, the plane of section being indicated by the line 2-2 of Figure 1.

Figure 3 is a detail partly in vertical section, showing the disk mounting.

Figure 4 is a detail partly in vertical section, showing part of the driving means for the disk conveyor.

Figure 5 is a detail in elevation, showing one of the brackets for supporting the steam pipes.

Figure 6 is a detail in vertical section showing the method of mounting the drip pan.

Broadly considered, my exhaust box comprises a housing in which a plurality of rows of tangentially arranged toothed carrier disks are placed. The disks provide means for conveying the cans through the housing, and in alternate rows the disks revolve in one direction, while in the other rows the disks revolve in the opposite direction. The disks in any one row are not in mesh with each other, but with the two adjacent disks in the adjoining row. A drive shaft extending transversely across the rows below the disks is suitably geared to a disk structure preferably in two alternate rows, so as to distribute the strain of the driving force, all of the disks then acting as a single gear train, driven by force applied at two different points in the train. The driving shaft is driven through suitable clutch mechanism by a pulley connected to any suitable source of power. The spacing of the disks is such that a straight line drawn between the centers of rotation of corresponding disks in alternate rows is substantially tangent to the adjacent disks of the other rows. Steam pipes for distributing jets of steam within the housing, are arranged coincident with planes cutting the centers of rotation of corresponding disks in alternate rows. These pipes are supported at their outer ends on suitable headers extending longitudinally of the outer row of disks, and at the opposite end, each pipe terminates in a block which is supported on a bracket projecting upwardly from a transverse bar below the disks. There are a num-

ber of these bars which also serve to support the bearings in which the disks are journaled. A guide rail is arranged on these pipes and directs the cans on the disks back and forth transversely across the housing, the end disks, which are of course the disks in the outer rows, carrying the cans thru an arc of approximately 300° , receiving them at the end of one trip across the housing and starting them backwardly on the return trip.

As will be seen from an inspection of Figure 1 of the drawings, there are only two disks in the assembly within the housing, of which at least one-half is not of use in carrying the cans forward; the other disks being useful for this purpose over the greater part of their surfaces. This gives a large capacity relative to the floor area of the machine, a result also materially affected by the fact that there are a relatively large number of disks, which are individually relatively small in diameter.

In detail my exhaust box comprises a framework, including end rails 2 and side rails 3. Legs 4 suitably braced by cross ties 6 support the frame on the floor. Spaced transversely across the frame at suitable intervals are bars 7 which preferably are of rectangular section, and which are secured in the side frame members 3 by suitable brackets 8. Firmly clamped on these bars by the bolts 9 passing thru the caps 11, are the brackets 12, each of which is preferably integrally formed with a vertical bearing box 13. As shown in Figure 1, the brackets alternate on each side of the bar and in the present embodiment of my invention there are four brackets on each bar, altho I may use six or even eight.

Each bearing box 13 as shown in Figure 3 is formed with a chamber 14 intermediate its ends; and as shown at the right hand end of Figure 1, each two chambers are connected by a conduit 16, into the middle portion of which, a conduit 17 feeds lubricant from an oil cup 18 conveniently accessible at the side of the machine.

Journalized in the bearing box on each side of the chamber is a shaft 19, on the upper end of which is fixed the carrier disk 21 slightly concave as shown, and provided on its periphery with the spur gear teeth 22, preferably beveled slightly on the upper sides.

The disk is provided with a hub 23 from which depends an annular flange 24, enclosing the upper end of the bearing, so that water splashed or condensed on the disk cannot enter the bearing. The bearing is further protected by the packing ring 26 interposed between the upper end of the bearing and the disk hub within the flange. A spiral groove 27 on the shaft carries lubricant over the upper portion of the shaft and seepage by gravity insures lubrication of the lower portion.

The lower end of the bearing box is closed by the plug 28 in which is seated the ball 29, and a set screw 31 adjustable in the lower end of the shaft seats on the ball. There is thus provided a thoroly lubricated substantially frictionless adjustable thrust bearing at the lower end of each shaft.

The radius of each carrier disk is but little greater than the diameter of the largest container to be handled, and the arrangement of parts is such that in plan view, the disks are arranged in an even number of rows, preferably four or six, the disks in any row being out of engagement with each other, but in mesh with two adjacent disks in the adjoining row. Thus all the disks are geared together in a single gear train, and the direction of rotation of the disks in one row in opposite to that of the disks in the adjoining row or rows, and a line passing thru the centers of corresponding disks in alternate rows is substantially tangent to each of two disks in the other rows.

Since all the disks are connected, driving one disk will drive the entire train, but in order to distribute the stress, I prefer to drive at two points. Two of the disks 21 are mounted on shafts 36 which extend downwardly thru the bearing box 37. A bevel gear 38 is fixed on the lower end of the shaft and a ball thrust bearing 39, protected by the packing ring 41, held in place by the split spring ring 42, is interposed between the hub of the disk and the upper end of the bearing. The bearing box is otherwise similar to the box 13, already explained.

Extending across the machine below the gears 38, which preferably are arranged on shafts of disks in alternate rows, is a shaft 43, on which are fixed gears 44 in mesh with the gears 38. The velocity of the shaft is cut down by connection thru the gears 46, with the drive shaft 47, between which and the driving pulley 48, is interposed the clutch 49, controlled by the long rock shaft 50, having the handles 51 at the ends of the machine, so that the operator can quickly reach a control handle from any point about the machine.

Extending longitudinally along the outer edge of the outer row of disks on each side, and supported on brackets 52, are header pipes 53 and 54. These pipes are joined by a cross pipe 56, below the disks, connected by the pipe 57, with a suitable source of steam under pressure. Extending from the pipe 53 transversely across the disk are pipes 58, spaced a little above the surface of the disk and coincident with a vertical plane determined by the axes of rotation of corresponding disks in alternate rows. The outer end of each pipe 58 is carried in the top of a bracket 59 projecting upwardly between the disks, and clamped at its lower end to a cross bar 7, on which adjustability is secured by the screws 130

61, so that the pipe may be properly lined up with the disks.

In a similar manner, pipes 62 are supported at one end in the pipe 54, and extend across the disks, between the pipes 58, to similar supporting brackets. All the branch pipes 58 and 62 are perforated so that live steam is admitted into the exhaust box thru them.

Mounted on the brackets 63 secured to the two header pipes and on the brackets 59, are the guide rails 66 and 67 evenly spaced apart and extending continuously thru the machine from the feed disk 68 to the discharge disk 69. These rails extend around the outer half of the peripheries of the disks in the outer rows and lie close to the steam pipes 58 and 62. The distance between the rails is slightly greater than the largest can to be handled and slightly less than the radius of the disks, so that as the containers are carried over the revolving disks they travel in substantially a straight line across the rows, then circularly around the disk in the outer row and back again in a straight line to the other outer row. At the left hand side of Figure 1, the arrows show the direction of the can travel.

It will be observed that as the can moves across the rows of disks it passes from one disk as to which it is on one side of the center, to the next disk, as to which it is on the opposite side of the center, these disks revolving in opposite directions.

Because of the relatively large number of disks counting transversely, and their small size relative to the size of the cans carried, there is a minimum of waste, or inactive space, on the disks; and in a packing plant this economy of space occupied is of very great importance, since it gives large capacity for the amount of floor area occupied.

At one end of the exhaust box a feed disk 68 is arranged, on which the entering cans are placed or fed, and at the opposite end, a receiving or discharge disk 69 carries the treated cans forward to the next step in the canning process. In order to confine the steam within the device, side walls 73 and end walls 74 are secured to the frame, extending upwardly far enough to clear the cans in the box. The upper edges of the side and end walls are provided with a channel or edging 76, and a cover 77, having a down turned flange about its edge, is fitted into the channel edging, so as to make a tight closure on the box and at the same time one which is easily removable.

In order to prevent leakage of steam from the exhaust box, bottom pans 78, are hung from the side frames on each side of the shafts 43 and 47. The space between the adjacent edges of the pans is filled with the inverted pan 81, supported on the side frame members 3 as shown in Figures 2 and 6. Since the pans 78 must be removable to give access to the various bearings enclosed by

them, means are provided for holding them in a readily detachable manner. Referring to Figure 6, the side edges of the pans are provided with reinforcing angle irons 82 on which are carried the hooked arms 83. Fixed on the side frame members 3 are studs 84 over which the hooked arms may be engaged. On the opposite side rails 3 are pivotally mounted latches 86, adapted to be engaged under the edge of the reinforcing angle iron 82 on that side. By swinging the latches to clear the edge of each pan 78, they may be lowered sufficiently to permit the opposite sides to be unhooked, so that the pans may be removed to give access to the under portion of the machine.

I claim:

1. An exhaust box for containers comprising a casing, an even number of rows of tangentially arranged carrier disks arranged longitudinally in said casing, means for rotating the disks in alternate rows in one direction and in the other rows in the opposite direction, a header pipe extending longitudinally of the box, perforated transverse branch pipes extending from the header and overlying the peripheries of disks in the odd numbered rows and the centers of the disks in the even numbered rows except the last row, and means for supplying said pipes with steam.

2. An exhaust box for containers comprising a casing, an even number of rows of tangentially arranged carrier disks arranged longitudinally in said casing, means for rotating the disks in alternate rows in one direction and in the other rows in the opposite direction, a header pipe extending longitudinally of the box, perforated transverse branch pipes extending from the header and overlying the peripheries of disks in the odd numbered rows and the centers of the disks in the even numbered rows except the last row, means for supplying said pipes with steam, and a rail for guiding the cans on said disks supported on said pipes.

3. An exhaust box for containers comprising a frame, a plurality of rows of tangentially arranged carrier disks, a bearing box in which each disk is journaled, a bar extending transversely across said frame below the corresponding disks of each row, and brackets on each bar for supporting the bearing boxes of the overlying disks.

4. An exhaust box for containers comprising a frame, a plurality of rows of tangentially arranged carrier disks, a bearing box in which each disk is journaled, a bar of rectangular section extending across said frame below the corresponding disks of each row, brackets integral with said bearing boxes, and means for clamping to each bar the bearing box brackets of the overlying disks.

5. An exhaust box for containers comprising a casing, a plurality of tangentially dis-

posed disks in said casing arranged in two outer rows and an even number of rows between the outer rows, means for rotating the disks in alternate rows in one direction and in the other rows in the opposite direction, and a continuous guide arranged adjacent the disks so that portions of the guide are disposed adjacent each disk in the outer rows to retain the containers thereon during at least one-half of its revolution, said guide having straight portions for directing the containers from the disks in the outer row in a straight line across the disks of the intervening rows to the disks of the opposite outer row.

In testimony whereof, I have hereunto set my hand.

WENZEL F. WEISS.
